(No Model.)

T. WILSON.

GAS BURNER.

No. 604,102.

Patented May 17, 1898.

FIG. 1.

UNITED STATES PATENT OFFICE.

THOMAS WILSON, OF PHILADELPHIA, PENNSYLVANIA, ASSIGNOR TO THE PENNSYLVANIA GLOBE GAS LIGHT COMPANY, OF PENNSYLVANIA.

GAS-BURNER.

SPECIFICATION forming part of Letters Patent No. 604,102, dated May 17, 1898.

Application filed February 1, 1897. Serial No. 621,429. (No model.)

To all whom it may concern:

Be it known that I, THOMAS WILSON, of the city and county of Philadelphia, State of Pennsylvania, have invented an Improvement in Gas-Burners, of which the following is a specification.

My invention has reference to gas-burners; and it consists of certain improvements which are fully set forth in the following specification and shown in the accompanying drawings, which form a part thereof.

The object of my invention is to provide means for regulating the flow of gas to a Bunsen burner of a class of burners especially adapted to incandescent lighting. It has heretofore been customary in burners of this class to provide means for supplying to the burner a fixed quantity of gas and varying the combustion by adjusting the air-supply. Experience with outside or street lighting, however, has demonstrated the advantage of maintaining a fixed air-supply and an adjustable gas-supply for proper rendering of the refractory mantle incandescent under the varying gas-pressure in the mains. In street-lamps it is difficult to provide means for securing this regulation in a manner which shall be capable of ready adjustment without dismantling the lamp. By my improvement, however, I secure the desired end in a most efficient and practical manner.

In carrying out my invention I provide the Bunsen burner with a gas-port, through which a needle-valve extends and by which the size of the orifice is regulated. The base of the Bunsen burner is adjustable upon the support or thimble of the needle-valve, whereby the turning of said base will secure the necessary relative adjustment of the gas-orifice upon the needle or tapering valve. The support or thimble of the needle-valve is made hollow and communicates with the gas-supply pipe. It is further provided with apertures through which the gas passes from said supply-pipe to the Bunsen burner.

My invention also comprehends other details of construction in a burner of this character, all of which will be better understood from the accompanying drawings, in which—

Figure 1 is an elevation of my improved

gas-burner. Fig. 2 is a sectional elevation of same, and Fig. 3 is a perspective view of the needle gas-valve for the Bunsen burner detached.

A is the main-valve casing and is adapted to be screwed upon the top of the gas-supply pipe and is provided with a rotary valve B, movable by a lever b for turning on or off the gas, as is customary. Screwed upon the top of this casing A is a thimble C, upon which is centrally mounted at the top a needle-valve E. The top of the thimble is perforated, as at e, about the needle-valve, so as to allow the gas to pass freely upward. Screwed upon the thimble C is an inverted valve-cap D, which is provided at the top with a central aperture G, through which the point of the needle-valve extends and by which the flow of gas to the Bunsen burner is controlled. The cap D forms the base of the Bunsen burner and is provided with projecting arms d, which may be pressed upon for rotating the cap with the object of adjusting the same vertically upon the stationary needle-valve. In this manner it is not necessary for the needle-valve to extend downward for operation from below, as has heretofore been customary with the needle-valves. The Bunsen-burner tube H is secured upon the cap D at F and is provided with the air-apertures h, which admit the requisite quantity of air to the Bunsen burner simultaneously with the upflowing gas from the orifice G. The heating-gas so produced is burned at the main burner K for rendering incandescent a mantle L of refractory material.

I is a shield supported upon the Bunsen burner and open at the bottom, as at i, for the entrance of air to the apertures h. Surrounding this shield I is a cylindrical screen J, which is designed to prevent the entrance of insects, dirt, &c., to the Bunsen burner.

The Bunsen burner, including the cap D, may be freely revolved upon the thimble G, under the adjusting action, so that the entire burner is somewhat raised or lowered in the adjustment, but not sufficiently to be perceptible to the general appearance of the structure as a whole.

N is a by-pass from which leads a perfo-

rated tube M, extending upward and into the burner structure adjacent to the main burner K for the purpose of igniting the gas flowing from the main burner. In practice the gas is first admitted to the by-pass, and after the light is applied to the tube M the gas is admitted to the main burner and thereby ignited, after which the gas to the by-pass is shut off. The tube M, extending up through the burner structure P, holds the same from rotating while the Bunsen burner itself is rotated for adjustment.

As shown, my improvements are applied to a structure in which there is a single burner in the lamp. In cases where there are two or more burners the customary Y-shaped tubular frame is screwed upon the top of the casting A, as indicated in United States Patent No. 597,430, dated January 18, 1898, and the thimbles C, screwed upon the upper nipples of the said Y-shaped tubular frame, and therefore the pipes leading to my improved burner would be modified to suit the usual location of the burner relatively to the main supply - pipe. It is, however, excellently adapted to the construction in which a single burner is used, and where it would be utterly impossible to arrange the needle-valve to be rotated without objectionably increasing the connection between the Bunsen burner and the main valve A and inserting an irregular tubular passage, which is not desirable.

By my construction the vertical height of the entire structure is reduced to a minimum consistent with good practicable operation and without interfering in the slightest manner with the necessary adjustment which is so essential in practice. Ordinarily the shield I is provided with a valve to control the entrance of the air at *i*; but in outdoor lighting it is desirable to leave the air-entrance of uniform area and adjust the gas-supply to compensate for variations in the pressure and richness of the gas. In this manner a more constant and uniform heating of the refractory mantle is secured and with less liability of its becoming injured or blackened.

While I prefer the construction shown, I do not limit myself to the mere details there-

of, as they may be modified without departing from the principles of my invention.

Having now described my invention, what I claim as new, and desire to secure by Letters Patent, is—

1. In a gas-burner, the combination of a vertically movable and rotatable Bunsen burner having a gas-aperture at the bottom, a main gas-pipe leading to the Bunsen burner, a fixed needle-valve arranged upon the main gas-pipe and extending into the aperture in the Bunsen burner, an air-valve carried by the Bunsen burner, lateral projections from the Bunsen burner below the air-valve for rotating it, a main burner loosely supported upon the Bunsen burner, an incandescent mantle supported over the main burner, and means to hold the main burner and mantle against rotation when adjusting the Bunsen burner upon the needle-valve. 55

2. In a gas-burner, the combination of the main gas-pipe and valve, a by-pass leading therefrom, an auxiliary igniting-pipe leading from the by-pass to the main burner, a fixed needle-valve arranged upon the gas-pipe, a Bunsen burner adjustable vertically upon the fixed needle-valve, and a main burner supported by the Bunsen burner and held against rotation by the auxiliary igniting-pipe. 70

3. In a gas - burner, a stationary needle-valve secured centrally upon a perforated thimble fitted to the gas-pipe, a Bunsen burner having a small central gas-orifice at the bottom receiving the point of the needle-valve and provided with a screw-threaded adjusting connection upon the thimble whereby it may be rotated and thus vertically adjusted upon the needle-valve, a mantle adapted to be heated by the gas from the Bunsen burner, screened air-passages to lead air to the Bunsen burner adapted to be rotated with the Bunsen burner, and means to hold the mantle stationary when the Bunsen burner is rotated during adjustment. 85

In testimony of which invention I have hereunto set my hand.

THOMAS WILSON.
